UNITED STATES PATENT OFFICE.

MICHAEL NEWELL ELLARD, OF CONCORD, NEW HAMPSHIRE.

BOTTLE-STOPPER.

SPECIFICATION forming part of Letters Patent No. 566,152, dated August 18, 1896.

Application filed February 4, 1896. Serial No. 578,009. (No model.)

To all whom it may concern:

Be it known that I, MICHAEL NEWELL ELLARD, a subject of the Queen of Great Britain, and a resident of Concord, county of Merrimac, and State of New Hampshire, have invented certain new and useful Improvements in Bottles and Bottle-Stoppers, of which the following is a specification, reference being had to the accompanying drawings, forming a part thereof, in which similar letters of reference indicate corresponding parts.

This invention relates to improvements in bottles and bottle-stoppers, the object of the invention being to provide means whereby a bottle may be effectually sealed and corked in such a manner as to require a purchaser or user to destroy a portion of the bottle before removing the stopper and the contents thereof.

20 The device will be simple in construction, inexpensive, and operative, and by its use certain frauds now practiced by unscrupulous persons upon bottlers of proprietary liquid products by the refilling and reuse of their marked bottles may be prevented.

The invention will be hereinafter fully described, and specifically set forth in the annexed claims.

In the accompanying drawings, forming 30 part of this application, Figure 1 is a vertical elevation of my improved bottle - stopper. Fig. 2 is a vertical sectional elevation on a line $x-x$ of Fig. 1, and Fig. 3 is a vertical sectional elevation of a bottle having my improved stopper attached thereto.

In the practice of my invention I provide a vertical rod A, having a button a upon its lower end and a head a' upon its upper portion. Above this head is formed another button a². To the button a² is secured a cap B, of rubber or other flexible material, and to the button a is secured a cork or stopper C. This said stopper will be of a diameter slightly larger than the interior diameter of the neck 40 of the bottle, whereby when it is forced into engagement with said neck the contents of the bottle will be effectually sealed and said contents will not be permitted to come in contact with the metallic portions of the stopper.

45 As a means for retaining the stopper within the bottle said stopper has depending from

its head a' two spring-metal arms D, which arms have formed integrally therewith upon their lower ends outwardly-projecting lugs d, which lugs are adapted to engage with an annular groove e, formed in the neck of the bottle E. These said springs are secured to the head a' by means of a rivet a³.

In the operation of the device the bottle is first filled to a desired height. The stopper 60 is then forced down into the neck thereof until the lugs d of the springs D are in engagement with the annular groove e, the cork C being tightly pressed within the neck of the bottle below the said groove and the cap B 65 being in close engagement with the mouth of the bottle, whereby the bottle is effectually corked and the stopper thereof cannot be removed until the neck of the bottle is broken, and owing to the thinness of the neck at the 70 point e' the fracture will always occur upon an approximately straight line at said point. After breaking the bottle in the manner described the stopper as a whole can be readily removed, and it can be used again for an indefinite number of times.

I do not confine myself to the specific details of mechanical construction as described above and illustrated in the drawings, as it will be obvious that under the scope of my invention I am entitled to make slight changes in structure.

Having thus described my invention, what I claim as new, and desire to secure by Letters Patent, is—

1. The combination of a bottle having an annular groove in its neck; with a bottle-stopper comprising a vertical rod having a flexible cap at its upper end and a flexible cork at its lower end and spring-metal arms secured to its upper portion, said arms having lugs upon their outer ends adapted to engage with the said annular groove of the bottle; substantially as shown and described.

2. A bottle-stopper comprising a vertical rod having a cap upon its upper portion and buttons upon its upper and lower ends, said buttons having respectively a flexible cap and a flexible stopper secured thereto and said head having spring-metal arms depending therefrom, which arms have lugs thereon adapted to engage with an annular groove in

the neck of the bottle; substantially as shown and described.

3. In a bottle-stopper, the combination of the vertical rod having buttons at both ends thereof and a head at the top portion thereof, said head having spring-arms with lugs upon their outer ends and with a flexible cap and a flexible stopper secured respectively to the said upper and lower ends, the whole adapted to engage with a bottle having an annular

groove in its neck; substantially as shown and described.

In testimony that I claim the foregoing as my invention I have signed my name, in presence of two witnesses, this 1st day of January, 1896.

MICHAEL NEWELL ELLARD.
